UNITED STATES PATENT OFFICE.

HENRY ALBERT, OF CRESCENT CITY, ASSIGNOR OF ONE-THIRD TO THOMAS R. HAYES, OF PASADENA, CALIFORNIA.

CAN-LABELING MACHINE.

SPECIFICATION forming part of Letters Patent No. 445,418, dated January 27, 1891.

Application filed May 7, 1890. Serial No. 350,927. (No model.)

To all whom it may concern:

Be it known that I, HENRY ALBERT, a citizen of the United States, residing at Crescent City, Del Norte county, State of California, have invented an Improvement in Can-Labeling Machines; and I hereby declare the following to be a full, clear, and exact description of the same.

My invention relates to the class of machines for pasting the labels on cans of all descriptions; and it consists in the novel features of construction, arrangement, and combination hereinafter fully described, and specifically pointed out in the claims.

15 The object of my invention is to provide a simple and effective machine of this class.

Referring to the accompanying drawings for a more complete explanation of my invention, Figure 1 is a perspective view of my machine. Fig. 2 is a view of the paste-roller and can-puller. Fig. 3 is a longitudinal section of the machine. Fig. 4 is a side elevation of the switch. Fig. 5 is a plan view showing the centering-inclines. Fig. 6 is a 20 cross-section of the machine. Fig. 7 is a perspective view of the label holders or locks and their mechanism. Fig. 8 is a view showing the tilting platform of the label-box. Fig. 9 is a view of paste-feed rolls P and p'. Fig. 10 is a view showing the adjusting mechanism of roll P. Fig. 11 is a view showing the adjusting mechanism of pasting-roller C.

30 A is the frame of the machine, having its upper portion formed into a runway a for the cans. Within this runway is adapted to be reciprocated a frame B, which carries in its rear portion the pasting-roller C and has attached to it the can-puller D.

The frame B has on its sides carrying-rollers b, which are mounted in track-grooves a' in the sides of the runway, so that said frame may be moved back and forth with the least amount of friction. Its movement is effected by the following mechanism: Extending rearwardly from it is a long guide-stem b', the rear end of which passes through a suitable guide-socket at the rear of the main frame A. Mounted in rear standards a² of the main frame is a shaft E, having on one end a hand-crank e, as here shown, or a belt-pulley, in order to apply power to the device. Its other

end has a suitable fly-wheel. The shaft E has a long crank e' at its center, provided in its outer end with an anti-friction roller e². Mounted in the top of the standards is a rock-shaft F, to which is secured a downwardly-extending and longitudinally-slotted lever f, which receives the anti-friction roller of the crank e', said crank playing up and down in the slotted lever and thereby vibrating it with its rock-shaft F above. The lower end of this lever is connected by a link f² with the guide-stem of the frame B. Now by operating the shaft E the frame is reciprocated in the runway.

65 The particular advantage of this construction may be thus stated: The stroke of the guide-stem b' is quite long, and it would take a crank with a large sweep if connected ordinarily; but in my device I have but a comparatively small sweep and the fall and rise of lever f are very slight. This gives a more direct pull on the stem. The pasting-roller C, which is carried in frame B, is so mounted as to be vertically adjustable. In the sides 70 of the frame are made grooves c, in which are the bearing-blocks c', adapted to be moved up or down by set-screws c². The end spindles c³ of the roller C extend into the grooves and rest on the blocks. The roller can by 75 these means be nicely adjusted, may accommodate itself to the surface over which it travels, and may be removed when required. By making the grooves c inclined slightly, as shown, the roller can be kept hugged up close 80 to the feed-roll of the paste car, hereinafter described.

85 The can-puller consists of side plates and top bars, said bars being separated sufficiently to allow of the intervention of the top friction and pressure roller d, the ends of which are mounted freely in slotted bearings d', so that said roller may rise and fall to provide for different-sized cans, being controlled, however, in this movement by springs d², 90 bearing upon its ends, so that it is normally held down to place with its lower surface projecting below the top bars and held positively on top of the can. The can-puller is connected with the frame B by a pivotal connection formed by rearwardly-extending arms d³, pivoted at their rear ends to the said 95 100

frame, so that the can-puller may bodily rise and fall through an arc in a vertical plane.

Upon the inner surface of the side plates of the can-puller near their upper portion 5 are the four small rollers d^5 , which, when the puller-frame is dropped down upon the can, bear on said can near each end and roll and guide it along. Its rolling action is thereby insured and all sliding prevented. The small 10 rollers may be separated sufficiently to provide for different diameters of cans and for any unevenness, such as a drop of solder. They could extend across the whole length of the cans, but are preferably located at the 15 end. They are above the can's center to insure its rolling. The top roller d is covered with felt or other suitable material, or it may be made of rubber.

The operation of the machine as far as described is as follows: At its front end it is provided with an inclined guide-channel G , in which the cans are placed and down which they run into the forward end of the runway a . Here a suitable mechanism, to be presently described, is located, whereby but one of the cans is allowed to be drawn forward at a time. The frame B being run forward, its can-puller comes down upon the top of the can, the ends of which fit between the sides 25 of the puller and between the small rollers, while the top roller bears upon the top of the can. The frame being now drawn backwardly draws the can with it positively, causing said can to roll through the runway and pressing 30 it down positively on the label.

Now, in order to allow the can-puller to get above, so as to fall down upon the can, I have the following construction: The ends of the can-puller are provided with carrying-rollers d^4 , which travel in the track-grooves a' of the runway and hold said can-puller down. In the sides of the runway and above the track-grooves a' are the upper track-grooves a^3 . Near their rear ends these grooves 45 communicate by a switch-bar a^4 , which is pivoted at a^5 , so that it may swing. The lower end of this switch-bar lies normally upon the lower track-groove a' , its point being flush therewith, while its upper end extends beyond its pivot and rises above the level of the upper track-groove. At their forward ends the two track-grooves communicate by a groove a^6 , the lower front edge of which is beveled, as shown. Now on the backward or 50 inward stroke of the frame the rollers b of the said frame and the rollers d^4 of the can-puller all travel in the lower grooves a' , in which position the puller lies down upon and in contact with the can. When the back of the 55 stroke is reached, said rollers simply raise the swinging switch-bars a^4 and pass under and beyond them; but upon the return or forward stroke the rollers d^4 of the can-puller first come in contact with the ends of the 60 switch-bars and travel upon them, thereby swinging the can-puller portion of the frame B upwardly, so that its rollers pass into the

upper track-groove. As they mount the inclines of the switch-bars and pass beyond their pivotal center the weight of the can-puller is sufficient to tilt the bars, whereby their lower ends are raised from the lower track-grooves, and the rollers b of the frame B at this moment reaching this point pass under the switch-bars and continue forwardly 75 in the lower track-grooves, thereby carrying the paste-roller back and forth constantly in the same plane; but the can-puller portion is raised to a higher plane. When it reaches the extreme forward end of the stroke, these 80 rollers drop down through the connecting-grooves a^6 , so that the can-puller comes down to its position on top of the can. The vertical automatic adjustment of the friction-roller of the can-puller provides for different diameters of cans. The bevels of the connecting-grooves a^6 avoid any tendency of the rollers in passing them to stick or catch. 85

The mechanism by which the cans are fed one at a time is as follows: Under the forward end of the runway is mounted a rock-shaft H , which has extending forwardly and back from it the arms h , the ends of which are suitably connected, as by a slot-and-pin connection at h' , with the stop-plates h^2 , which project at a forward inclination up through the runway. This rock-shaft has a crank-arm h^3 , with which a long link or rod h^4 is connected, the forward end of which is provided with a long slot in which the lower end of a swinging arm h^5 freely plays, the upper end of said arm being forked and operated by an eccentric h^6 on the end of the power-shaft E . Now by operating said shaft the power is transmitted through the devices described to 90 rock the shaft H under the forward end of the runway and thereby to alternately project upwardly and withdraw the two plates h^2 . The outer one is projected to hold the series 95 of cans back, while the inner one is withdrawn 100 to allow the movement of the first can. Then when another can is to be fed the inner one is raised, so as to stop the can temporarily, while the outer one is lowered to allow it to come down to place. The object of inclining 105 the stop-plates h^2 is to prevent the cans from moving out of place or slightly moving forward when the inner plate is withdrawn and before the outer one has been raised to hold the row of cans back. Before the inner plate 110 has left the edge of the can the outer plate will have reached the surface of the can behind, so that it cannot roll. The connections 115 shown are such that the plates move truly and their operation is effected only near the 120 ends of the stroke.

Now, in order to center the cans as they roll into place to be engaged by the can-puller, I have the following device: In the sides of the guide-channel G , between the two stop-plates h^2 , are the centering-inclines g , which are pivoted to the sides, so that they may be moved to and from each other. This movement is effected by a right and left hand 130

threaded screw g' , which engages them both. As the cans roll down the channel they pass between the inclines g and are centered by them. The adjustment of the inclines provides for different lengths of cans.

5 I is the label-box, consisting of a hollow casing extending downwardly directly under the runway of the machine, its top being on a level therewith. This box has a door I' and 10 is provided with a vertically-movable false bottom i , which carries the pile of labels. Its surface is preferably covered with felt or other material, such as rubber or cloth.

15 The labels are held up to position in the runway, so that the paste-roller will pass over the topmost one of the series, by the following means: The movable bottom i has a downwardly-extending stem i' , which passes through the bottom of the label-box and carries upon its lower end a guide-pulley i^2 . Secured to the bottom of the label-box at one 20 end is a cord i^3 , which passes downwardly under the pulley i^2 of the stem and up over a guide-pulley i^4 under the box at its other 25 end and carries a weight W , which is connected with it by a simple hook-connection, as shown, whereby said weight may be readily removed and replaced again when required, as when the labels have to be supplied to the 30 box, and the movable bottom dropped down. The effect of this weight is to exert a constant upward tendency or strain upon the stem, and consequently to keep the false bottom i within the label box pressed upwardly, 35 so that the label pile shall always be in position to have the paste-roller pass over the topmost one. This strain or power being constant, the feed is automatic, and as each label is taken off by a can the remainder of the 40 pile is kept constantly held up to place. There is a peculiar advantage in this power device, which may be stated as follows: When the pile of labels is a large one, it has more weight than when it is decreased to a smaller 45 pile. Consequently at first sight it might appear that if a weight sufficient to raise the entire or half pile were employed then as the pile decreased in weight the weight W would be too great and would exert an unequal 50 and excessive upward power; but, on account of the arrangement of the string which suspends the weight, it will be seen that when the label pile is greatest, and consequently the stem of the movable bottom is pressed down, 55 the string will assume an inclination nearer the vertical, and consequently the power of the weight will be greater in this position, so that it will be sufficient to hold up and keep raised the entire pile; but as the pile decreases in 60 bulk and the movable bottom and stem rise the string approaches nearer the horizontal, in which position the weight cannot act on it as effectively, and thereby its power will be decreased, so that it will hold up the decreasing pile with a constant power. Thus even 65 down to the last label there will be the same

constant power exerted to hold the pile up to the action of the paste-roller and can.

Now in order to form a stop for the label pile, so as to hold it exactly in the plane desired and yet relieve the topmost one as a can passes over it, I have the following locks or holders: J represents these locks or holders, and they consist of pieces of flat metal, preferably a little yielding, so as to have a slight play as the paste-roller moves over them. They extend from each side of the runway into its interior and lap over the top of the label pile. There are four or more of them, two being shown near each end, one at each side of the label pile. They are pivoted at j , so that they may swing from a horizontal plane, in which they overlap the labels, to a vertical plane, in which they release said labels.

85 The tripping mechanism of the locks consists as follows: The locks or holders have upwardly-extending stems j' , which engage sliding bars j^2 , the rear end of which is acted upon by a spring j^3 , the tendency of which is to hold the parts forward, so that the locks or holders remain in a horizontally-operative position. In the sides of the casing are pivoted the trigger-bars j^4 , the ends of which project into the runway a and into the path of the sides of the can-puller. The ends of these trigger-bars are connected by links j^5 with the sliding bars j^2 , whereby the latter are forced backwardly against the power of their springs, thereby raising the locks or holders to a vertical position and releasing the labels. It will be seen, therefore, that as the can-puller approaches the first pair of trigger-bars its sides, coming in contact with them, operate upon them in such a manner as to raise the first pair of locks or holders from the label pile, thereby freeing that end of the topmost label, so that the can following in the can-puller picks up that end of the label. As soon as the sides of the puller release the trigger-bars the locks or 100 holders spring back to position over that end of the next label. Then the sides of the can-puller come in contact with the next pair of trigger-bars and operate them so as to raise the locks or holders and release the other end 105 of the first label, and the can following rolls it up upon itself. As soon as the puller has passed the second set of trigger-bars the locks or holders thereof spring back to position and hold the next label. The under side of 110 the locks or holders may be roughened, if desired.

115 Now, in order to hold these locks or holders positively against any possible displacement or the upward force of the label pile, I have 120 the following positive catch mechanism: There is one for each lock. Pivoted in the side of the runway is the catch-bar K, having a beveled inner end which projects into the path of travel of the sides of the can-puller. It has a notched outer end or head k , which lies normally behind the vertical stem j' of 125

the lock or holder, and is held in this position by a small spring k' . When in normal position, therefore, these catches hold the locks or holders firmly; but just before the 5 sides of the puller come in contact with the trigger-bars j' , as heretofore described, they come in contact with the inner ends of the catch-bars, thereby turning them on their pivots, so as to release the stems of the locks or holders. When the latter return to place, the heads of the catch-bars spring in behind their stems and hold them. The can-puller sides miss all the trigger and catch bars returning, as the whole puller is then elevated.

15 I may find it advisable to use a swinging or tilting platform to rest the label pile upon instead of placing it directly upon the false bottom i . This platform is designated by i' , and it is pivotally connected at i'' , at the middle of its sides, to the bottom i , so that it will tilt from end to end. The object of this is as follows: As has been described, the label pile is resisted and held by four holders or locks, two being near each end of the pile, 20 one on each side. As the can rolls upon the label pile, the surface of which is slightly above the level of the runway, it presses the whole pile down away from the locks, and as one pair of locks are withdrawn and the other 25 pair do not bear on the pile, because it is pressed below their level, there is a chance for the next label below the topmost one to slide out of place. This would be the tendency when using the movable bottom i , for 30 the label pile would be depressed equally over its entire surface; but by using the tilting platform i' only one end of the pile would be depressed, while the other end would be raised into contact with the holders or locks, 35 thereby preventing any displacement of succeeding labels.

When using the tilting platform, its surface will be covered with felt or other material to enable the last label to be picked up 40 readily by the rolling can.

45 L is a vertically-movable guard-piece at the end of the label-box, extending all the way across, and which serves to hold the labels from being displaced endwise. This bar is 50 held normally up by a spring l and is adapted to be run down by the paste-roller and can as they pass over it.

55 In the runway, near its rear end, is an opening in which plays a movable discharge-platform M , which receives the can after it has picked up its label. This platform is mounted upon the upper end of a vertically-movable stem m , and is held normally in an elevated position by means of a string m' and suspended weight W' . The weight, however, is not sufficient to counterbalance the weight of the can, so that when the can rolls onto the platform its weight is sufficient to carry it down, and it then rolls off into the discharge-chute N . The weight W' then returns the platform for the next can.

60 In order to supply the paste-roller with

paste, I have the paste-car O . This is mounted upon the tops of the runway sides, and is adapted to be reciprocated back and forth 70 with the frame B by a suitable connection between it and said frame. That connection is formed by a downwardly-extending arm o from the car passing into a simple socket o' on the guide-stem of the said frame. The 75 paste-car is provided with small guide-wheels o^2 in front and with power-wheels o^3 at the back. These power-wheels are upon the shaft or axle of a second feed paste-roll P , which is in contact with the first feed paste-roll p , 80 operating within the paste-car, and also in contact with a third feed-roll p' , which lies in contact with the paste-roller of the truck-frame B . The rolls are to be covered with felt or any suitable material which will absorb paste. The second or middle paste-roll P is kept hugged up close to the first roll p by mounting its end boxes in elongated slots o^4 , so that they will slide, and controlling their movement and position by springs o^5 upon 85 adjusting-screws o^6 . Rotation is imparted to these several parts by means of the rolling action of the wheels o^3 on the feed-roll P . These wheels, in order to insure their positive rotation, are preferably provided with teeth, 90 which engage extended racks o^7 on the top of the runway sides. Thus the paste is kept constantly supplied to the paste-roller and all the parts are kept in motion, so that the paste is evenly distributed throughout the 95 several rollers. The third roll p' of the paste-car has a flange p^2 at each end to prevent the paste from running off the ends. The other roll plays inside of these flanges, and any paste getting onto its ends will be scraped 100 off by said flanges. To prevent the paste from dropping off the ends of the rollers, said ends are made concave. The peripheries of the paste-rolls are to be made with channels or grooves x around them under their felt or 105 other coverings. The rolls carry more paste when constructed in this way. These channels or grooves may be opposite each other or not and may be of any suitable number. The feed-roll p' is in contact with the paste- 110 roller C and effects its rotation, so as to receive the paste equally over its surface.

115 The general operation of the machine is as follows: The labels are supplied to the label-box through a door in one side thereof and 120 are inserted in such numbers that the movable bottom on which they rest is depressed to its lowest limit, and the top of the label pile is held in the surface of the runway by the locks or holders. Paste is supplied to the paste-car 125 and cans are fed into the guide-channel G . The parts are then set in motion, so that the puller drops over the first can, and as the frame B recedes the paste-roller passes over the topmost one of the label pile, thereby supplying it with paste. The can-puller operates the locks or holders, as heretofore described, 130 to release successively the ends of the topmost label and immediately lock the ends of the

underlying pile. The can following rolls over the labels and picks up the topmost one. This rolling is a positive one under the action of the can-puller, the top roller of which insures the 5 rotation of the can and its pressure upon the label from end to end, and also presses out the label smooth as the can rolls it up. When the frame has reached the backward limit of its stroke, the labeled can is received upon 10 the platform M and falls into the discharge-chute. The frame now proceeds upon its return-stroke, the can-puller rising to the higher track-groove, as heretofore described, so as to reach an elevation from which it can drop 15 down onto the next can; but the paste-roller continues at the same level and rolls over the labels again, so that it passes twice over the same label, once on each stroke. A further point of novelty lies in the provision of the 20 ledges a' directly under the track-grooves a' and upon which the lower edges of the can-puller sides rest and slide. These form firm bearings for the can-puller and prevent it from rocking or tilting, keeping it level. The 25 trigger-bars j' project into the runway just above these ledges, so that the sides of the can-puller must strike them.

Having thus described my invention, what I claim as new, and desire to secure by Letters Patent, is—

1. In a can-labeling machine, the combination of the can-runway, the label-box opening into said runway, the reciprocating frame in the runway, the paste-roller mounted in said 35 frame, and the can-puller connected with said frame, substantially as herein described.

2. In a can-labeling machine, the combination of the can-runway, the frame adapted to reciprocate therein, having a guide-stem, the 40 cranked power-shaft, the slotted lever in which the crank of the shaft works, and the link connecting the lever with the reciprocating frame, substantially as herein described.

45 3. In a can-labeling machine, the horizontally-reciprocating can-puller having a top roller for bearing on the can, substantially as herein described.

4. In a can-labeling machine, the horizontally-reciprocating can-puller having a vertically-adjustable top roller bearing on the can, substantially as herein described.

5. In a can-labeling machine, the horizontally-reciprocating can-puller having the 55 small rollers on the inner surface of its sides, substantially as herein described.

6. In a can-labeling machine, the horizontally-reciprocating can-puller consisting of the side and the separated top bars and intervening top roller adapted to bear on the can, substantially as herein described.

7. In a can-labeling machine, the horizontally-reciprocating can-puller consisting of the side and top bars and the top roller having 65 its ends mounted so as to slide vertically and springs controlling said ends, whereby the roller is kept pressed down on the cans

and may yield to different-sized cans, substantially as herein described.

8. In a can-labeling machine, the horizontally-reciprocating can-puller consisting of side and top bars, the top roller for bearing on the can, and the small rollers on the inner surface of the sides, substantially as herein described. 70

9. In a can-labeling machine, the reciprocating can-puller, in combination with the can-runway having tracks in which said can-puller operates, said tracks being so arranged as to guide the can-puller on its forward 80 stroke in a plane higher than on its return-stroke, and switches in said tracks to direct the can-puller from one track to another, substantially as herein described.

10. In a can-labeling machine, the reciprocating can-puller having end rollers, in combination with the runway in which said puller operates, the lower track-groove in the sides of the runway in which the can-puller rollers operate on one stroke, the upper track-groove 90 in said sides in which the rollers operate on the other stroke, the switch-bars connecting the two grooves at one end, whereby the can-puller is raised into the upper groove, and the grooves connecting said track-grooves at their 95 other ends, whereby the can-puller drops upon the can, substantially as herein described. 85

11. In a can-labeling machine, the reciprocating frame having a paste-roller and a can-puller pivoted to said frame, whereby it may 100 rise and fall, in combination with the can-runway having track-grooves in its sides for guiding the frame and can-puller, and switches in the grooves to direct the can-puller to a plane higher on one stroke than 105 on the other and to direct the paste-roller in the same plane, substantially as and for the purpose herein described.

12. In a can-labeling machine, the frame A, having the runway, with the upper and lower 110 track-grooves in its sides, the pivoted switch-bars connecting the grooves at one end, said bars resting their lower ends in the lower grooves and extending their upper ends beyond their pivots to a point above the upper 115 grooves, the grooves connecting the track-grooves at their other ends, in combination with the reciprocating frame mounted in the runway and having supporting-rollers traveling in the lower grooves, the paste-roller 120 carried by said frame, the can-puller having arms pivoted to said frame, whereby it may rise and fall, and having rollers adapted to pass from one groove to the other and operate the switch-bars to permit the passage of 125 the frame-rollers in the lower grooves, substantially as herein described.

13. In a can-labeling machine, the combination, with the runway thereof, of oppositely-moving inclined stop-plates in the path 130 of the cans, a rock-shaft and connections for moving the plates in opposite directions, oppositely-swinging inclines pivoted to the sides of the guide-channel, and the right and

left hand screws engaging said swinging inclines and adjusting them, substantially as herein described.

14. In a can-labeling machine, the combination of the runway, the reciprocating can-puller, the alternately-operating inclines and the swinging inclines pivoted to the sides of the guide-channel, and means for adjusting said swinging inclines, substantially as herein described.

15. In a can-labeling machine, the combination of a reciprocating piece in the can-runway, a label-box under said runway and communicating therewith, pivoted locks or holders extending from each side of the runway into the interior for controlling the label pile and operated to relieve it by the reciprocating piece, a vertically-movable bottom in the label-box, and a tilting platform carried by the movable bottom, substantially as and for the purpose herein described.

16. In a can-labeling machine, and in combination with a reciprocating piece in the can-runway and the label-box thereunder, the locks for holding the label pile, consisting of the swinging holders overlapping the sides of said pile, and a trip mechanism for said holders projecting into the path of the reciprocating piece, whereby said holders are operated to relieve the topmost label of the pile, substantially as herein described.

17. In a can-labeling machine, and in combination with a reciprocating piece in the can-runway and the label-box thereunder, the locks for the label pile, consisting of flat strips pivoted and overlapping the sides of the pile, and the means for operating said strips, consisting of the stems, the sliding bars with which the stems engage, the springs of said bars for returning them, the pivoted trigger-bars extending into the path of the reciprocating piece, and the links connecting said trigger-bars with the sliding bars, substantially as herein described.

18. In a can-labeling machine, and in combination with a reciprocating piece in the can-runway and the label-box thereunder, the pivoted locks for holding the label pile, the spring-controlled stems of said locks, the catch-bars holding said stems and having their inner ends projecting into the path of the piece, and the springs controlling said catch-bars, substantially as herein described.

19. In a can-labeling machine, and in combination with a reciprocating piece in the can-runway and the label-box thereunder, the pivoted locks for the label pile, having stems, the slide-bars connected with the stems, the springs controlling the slide-bars, the trigger-bars extending into the path of the reciprocating piece and connected with the slide-bars, and the spring-controlled catch-bars engaging the stems of the locks and projecting

into the path of the reciprocating piece, substantially as herein described.

20. In a can-labeling machine, the reciprocating frame having the swinging can-puller connected with it and the runway in which said frame and puller operate, in combination with the label-box, the locks or holders for the label pile, the trigger-bars extending into the path of the can-puller sides and connected with and operating the locks or holders, the upper and lower track-grooves in the runway sides, and the switches for directing the swinging can-puller from one groove to the other, substantially as and for the purpose herein described.

21. In a can-labeling machine, the runway having the upper and lower track-grooves and switches connecting them, in combination with the label-box, the locks or holders for the label pile, the trigger-bars projecting into the runway and adapted to operate the locks or holders, and a reciprocating swinging piece in the runway adapted to operate the trigger-bars and having rollers mounted and adapted to travel in the track-grooves, whereby said piece is directed from one groove to the other, substantially as and for the purpose herein described.

22. In a can-labeling machine, the combination of the runway having the track-grooves and switches connecting them, the reciprocating frame B, having the paste-roller and rollers traveling in the lower track-grooves, the can-puller pivoted to the frame and having rollers mounted in the track-grooves and adapted to be switched from one to the other to swing the can-puller, the label-box, the locks or holders for the label pile, and the trigger-bars for operating the locks or holders, said bars projecting into the path of and operated by the can-puller, substantially as herein described.

23. In a can-labeling machine, the can-runway having the track-grooves a' , with underlying ledges, in combination with the can-puller having the rollers traveling in the track-grooves and its sides resting and sliding on the ledges, whereby the can-puller is steadied and kept level, substantially as herein described.

24. In a can-labeling machine, the combination of the can-runway and the reciprocating frame therein with a paste-roller, the label-box under the runway, and the vertically-movable guard at the end of the label-box to prevent the end displacement of the labels, substantially as herein described.

In witness whereof I have hereunto set my hand.

HENRY ALBERT.

Witnesses:

GEO. A. LEON,
J. E. ELDREDGE.
